US0D1101579S

(12) **United States Design Patent** (10) **Patent No.:** **US D1,101,579 S**
(45) **Date of Patent:** **** Nov. 11, 2025**

(54) **REMOTE CONTROL FOR AIR CONDITIONER**

(71) Applicant: **Samsung Electronics Co., Ltd.**, Suwon-si (KR)

(72) Inventors: **Sangin Lee**, Suwon-si (KR); **Hyunsoo Kim**, Suwon-si (KR)

(73) Assignee: **Samsung Electronics Co., Ltd.**, Suwon-si (KR)

(**) Term: **15 Years**

(21) Appl. No.: **29/862,649**

(22) Filed: **Dec. 12, 2022**

(30) **Foreign Application Priority Data**

Jun. 16, 2022 (KR) 30-2022-0023939

(51) **LOC (15) Cl.** **10-04**

(52) **U.S. Cl.**

USPC **D10/50**

(57) **CLAIM**

The ornamental design for a remote control for air conditioner, as shown and described.

DESCRIPTION

FIG. 1 is a front perspective view of a remote control for air conditioner showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof;

FIG. 8 is an enlarged view of the encircled portion in FIG. 1;

FIG. 9 is an enlarged view of the encircled portion in FIG. 3;

FIG. 10 is an enlarged view of the encircled portion in FIG. 4; and,

FIG. 11 is an enlarged view of the encircled portion in FIG. 7.

The grayscale tones shown in the drawings represent a contrast in appearance.
